ICE CREAM TRUCK

Robert H. Heffelfinger, Memphis, Tenn.

Application August 18, 1955, Serial No. 37,565

Term of patent 14 years

(Cl. D14—3)

The figure is a perspective view of an ice cream truck showing my new design.

The side of the truck not shown is of the same configuration as that shown.

I claim:

The ornamental design for an ice cream truck, as shown.
